UNITED STATES PATENT OFFICE

HOMER A. HERR, OF PHILADELPHIA, PENNSYLVANIA, ASSIGNOR TO AUTOMATIC CENTRIFUGAL COMPANY, A CORPORATION OF DELAWARE

CONTINUOUS AUTOMATIC CENTRIFUGAL MACHINE

Application filed June 4, 1923. Serial No. 643,329.

My invention has reference to centrifugal machines and consists of features fully set forth in the following specification and the accompanying drawings forming part there-
5 of.

The object of my invention is to provide an automatic centrifugal, reliable in action, fool proof in service and efficient in its work; needless to say the fundamental object is the
10 saving of labor and economy of production.

In my Patents Nos. 1,246,267, 1,166,370, 1,286,626 and 1,212,638 I show an automatic centrifugal having two speeds. The speed ratios shown in the said patents are not fixed
15 and are, therefore, unreliable, particularly the slow speed. This is sometimes a very serious defect in service. My present invention overcomes all the troubles of this nature and makes a decided advance in the art, as
20 the slow speed rotation is by this invention made fixed, positive and reliable.

A second feature of my present invention is to have a specifically independent drive for the slow speed basket rotation and to pre-
25 determine positively the slow speed and the speed ratios.

A third feature is to have a common mech-
30 anism to control the two speeds successively but alternately, so when the high speed drive is in action the slow cannot be, and vice versa.

A fourth feature of my invention is a means to unlock the high speed driving mechanism from the basket it drives and place this mechanism in a neutral position,
35 which allows the momentum of the basket, at this time, to be the entire driving force, and to arrest this momentum. A fifth feature of my invention is to put a brake mech-
40 anism into action to arrest the basket momentum as soon as the high speed drive is disconnected from the basket.

A sixth feature of my invention is to con-
45 nect the basket with the slow speed driving mechanism after the basket momentum is arrested sufficient to bring the basket down to at or near the slow speed.

A seventh feature of my invention is to automatically permit the positive speed of the basket at any time to exceed the slow
50 speed drive without straining the driving

mechanism (which strain would brake the said mechanism) if the momentum of the basket is not arrested to such degree that the basket rotation under momentum is not as slow as the fixed slow speed drive.

55

An eighth feature of my invention is a feeding mechanism permitting variation, and a means for permitting instant adjustment of feed as to volume and time.

A ninth feature is an improved washing and spraying mechanism for sugar service and quick adjustment for volume of spray and time of spraying.

A tenth feature of my invention is a cleaning mechanism permitting the basket clean-
65 ing to take place at speed.

A further feature of my invention is a sim-
plified means for raising the valve in the basket bottom prior to basket cleaning.

Other features of novelty will be set out
hereinafter.

In the drawings like parts will be referred to by marks or figures of a corresponding kind in the different views.

Fig. 1 is a front elevation of the complete
70 machine to the top of the curb, and showing the water spray in position.

Fig. 30 is a plan of the momentum arresting 30 brake. Fig. 31 is a side view of the brake and section of the cap of the bearing chamber.

Fig. 32 is a side view of the cam, lever and link rod for lifting the basket bottom. Fig. 33 is a vertical section thru the spray. Fig. 34 is a front view.

Fig. 35 is a side view of trip cam. Fig. 36 is a plan of the spray valve actuating bar and Fig. 37 a side view of the same.

Fig. 38 is an assembly of the valve with 40 parts shown in Figs. 36 and 37. Fig. 39 is an assembly side view of the same.

Fig. 40 is a link detail.

Fig. 41 is a detail of the link bar which engages the clutch bars on the prime shaft.

Fig. 42 is an assembly of the prime shaft and 45 the clutch engaging and disengaging link bars, shown in Figs. 41 and 47.

Fig. 43 is a vertical section on the prime shaft on line X'' of Fig. 42.

Fig. 44 is a section on line X' of Fig. 42. Fig. 45 is a plan on the compound lever for 50 raising the clutch link shown in Fig. 47.

Fig. 46 shows the position of the dog on the clutch link shown in Fig. 47 after the said link has been raised and is ready for the succeeding cycle. Fig. 47 is a plan of the water spray and a section of the basket shaft.

Fig. 48 is an enlarged view of the clutch which operates the basket shaft 84 at the slow 55 speed.

Fig. 49 is an enlarged view of the clutch at high speed covering only the disc, ring and contracting lever.

Fig. 50 is an assembly detail of the rod 82 55 and its operating lever S'.

Fig. 51 is a link detail, partly in section to show the outwardly contracted hole p4.

Fig. 52 is a link detail and Fig. 53 is a part assembly section on line PX of Figs. 48 and 49.

A—A are the standards for the support of the mechanism of the machine. There are usually four of these standards, although there are other ways that the mechanism could be supported. The equivalent for these standards could be suspended from the usual channels which carry the motors. The object of these standards, or any equivalent mechanism, is to support the mechanism and the basket so that the basket is in the center of the curb. In practice it is designed to insert the mechanism, as a mechanical unit, between the curb and the motor support, so it can be applied to machines already installed, and thus convert manual operated machines into 80 automatic ones.

In the construction shown in Fig. 1 A', A' support the main bed plate B. This bed plate carries the basket shaft bearing and the main mechanism details of which will be described. The arms B' carry a second bed plate B2, which latter supports the brake wheel and its co-acting members. This frame also supports the driving mechanism for the slow basket speed. The bed plate B carries the bearing chamber 1, shown best in Fig. 24. This chamber consists of a cylindrical casting with its upper end contracted in diameter and its lower end carrying an inner flange 3. This frame supports a cap 4 by a series of 100 screws 5, which supports directly the entire bearing elements of the machine and, therefore, the basket B'''. The arc 6, determined by radial lines r' and r, forms the concave bearing seat for the bearing proper 8. The cap 4 is made of cast iron. The bearing phospher bronze 9 is an intermediate bearing resting in 8 and inset in the nut 10. Bearing 9 should be made of steel or close grained iron. The nut 10 is made of cast iron and is threaded to the shaft with lock screws (not shown) to prevent movement independent of shaft rotation. Of course I do not limit myself to the shaft shown in the drawings. Any type of self aligning bearing will answer my requirements, and bearings of this type are necessary in centrifugal machines. To insure oil being retained in the bearing chamber I insert a tube 11 in the cap 4 in an oil tight manner, shown only in Fig. 24, in section. I also provide a spreader 12, held by the boss B4 of the flange 25, and impinged by the nut 10, in a fixed position. This spreader rotates with the shaft and any oil that may pass over the top of the tube 11 passes down the inner side of the said tube into the basin formed by the shape of the collector 13. This collector carries a cap 14 which prevents oil therein splashing over the inner ring 13', forming 120 115 125 130

this part of the said collector, and all such oil is passed out of the port 15, see Fig. 24.

16 is a universal joint of standard make, the center of the joint, and, therefore, the center of the basket oscillation, is shown at 19, which is the intersection of the lines 18 and 17. The lines r and r' indicate tentative oscillation of the basket with point 19 as the radial center. The lower flange 16' of the universal joint, shown in Fig. 27, carries a series of holes h'' h''' . These holes receive the pins 20 of which there are as many as holes. The pins are tapered to readily seek their respective holes in assembly. The said pins are threaded into the nut 10 and coincide positionally with the holes in the flange 16'. This flange 16' is the lower flange of the universal joint of which the upper is 16'' and the center is 16. 16'' is bolted to the flange 21 of the shaft 22 which latter is bolted to the brake wheel 165 thru a flange 23, Fig. 4. In practice I find it best to weld the flange 21 to the shaft 22 and to key flange 23 to the said shaft, the latter carrying a suitable boss for such construction.

The nut supporting basket shaft 27, thru intermediate and coupling shaft 24, Fig. 24, carries an end extension 24, which is inserted in the hole 24', Fig. 27, in a snug fit, and this hole retains the coupling shaft B4 in alignment with the center of the joint 19. The flange 25, carried by the lower end of the union shaft B4, carries and has bolted to it the basket shaft flange 25'. This shaft supports the basket thru the arms 28, Fig. 7.

There are four or more of these arms all cast integral with the central boss 29, Fig. 7. The basket shell, or ring B''' is cylindrical and is welded to the ring 30, the latter being riveted to the flange on the ring 32, as shown in Fig. 7. The ring 30 is a plate disc with its circumference exactly concentric with the shaft center.

It is evident that when I wish to assemble the nut 10 and thereby connect the basket B''' to the universal joint 16, the pins 20 in the said nut 10 readily enter the holes in the bottom flange 16' and the bottom flange aforesaid readily enters the recessed part of the nut which forms its seat. It is also evident that when I wish to disconnect the basket from the said nut I remove the cap screws 5, the bearing 4, bearing 8, intermediate bearing 9 and then nut 10 with its pins can be readily withdrawn and the joint 16 and shaft 22 remain in position and intact. This construction facilitates repairs and accessibility to these parts. A detail description of the joint is not necessary, as it is of standard design.

Stabilizing the basket

Centrifugal baskets, at the time of loading and at other times, have a violent disturbance of their center of gravity and this produces

lurches of oscillation which may be dangerous. To avoid this and to increase the general efficiency I produce and provide a stabilizer. This stabilizer facilitates establishing the center of gravity of the mass of material under treatment. It consists of a central metallic bearing 33, Fig. 25, which fits the basket shaft loosely and oscillates with the said shaft. An outer annular casing 34 is a fixed retainer for the said bearing 33. There is an annular space 40 between the inner wall of the bearing 34 and the outer wall 33. These two adjacent walls should be machined concentrically, and somewhat recessed vertically, as shown at 40. Rubber tubular rings 35 and 36 are carried in the space formed by the outer wall of the inner ring and the inner wall of the outer ring aforesaid. The recess 40 holds the said rings in position. Dotted line 40'' represents the normal position of the inner ring when the machine is not in action and line 40' the position of extreme oscillation. If there is a disturbance of the center of gravity the rings 35 and 36 will quickly restore it, as is evident. The outer ring 34 is rigidly supported by a series of rods 41, connected to their support 42, which latter are bolted to the top of the curb 44 by bolts 43, as shown in Fig. 25 and in the assembled view, Fig. 25. These rods prevent the ring 34 from dropping into the basket and at the same time they hold the retainers in place and receive the thrust of the lurching of the basket.

A top plate 37 is bolted to the inner ring 33 and rests on the top of the outer ring 34. Now, inasmuch as the outer ring 34 is rigid and cannot vary its central position, by virtue of the rods 41 and the cap 37, which is provided with enlarged holes 45, the said cap can move in any direction in a horizontal plane, in unison with the oscillation of the shaft 27, which it surrounds and within the limits of the said shaft oscillation as limited by the rubber tubes 35 and 36. Needless to say that the force occasioned by the speed of the basket is absorbed by the rubber rings 35 and 36 and thru them transmitted to the curb 44.

I do not limit myself to this specific form or type of stabilizer, nor do I make specific claim in this application, but broadly a stabilizer in combination with other features of an automatic centrifugal, which I show. Nor do I limit the position of the stabilizer in its relation to the basket shaft. This is entirely aside and immaterial.

Washing the sugar in a sugar machine

Fig. 33 shows the sprayer I employ to wash the sugar. It consists of a hollow chamber 45 having a series of holes very small in diameter. The cap 46, which carries the holes should be curvilinear so the water as sprayed can reach the entire basket wall and the sugar thereon impacted. An adjustable shutter 47,

with proper gasket, is provided to regulate the volume of water flow and to vary the force and volume at the upper UA lower or UL position of the spray chamber. A feed pipe 48 5 conducts the water to the spray chamber from the valve 49 which is controlled by the automatic mechanism of the machine. 50 is the intake from the supply pipe to the water valve 49. This valve need not be special and 10 the quick acting lever gate valve of commerce is well suited for this work: such a valve is shown at 51, Fig. 38. The valve operating lever 52 is pivoted at 53 to the bed, B Figs. 38 and 33, or any other suitable support. The 15 link 54 carries a spring 55 and a spring compression adjuster 56, a collar 54', nut 54''. Now as the link pulls in the direction 54''' the valve lever 51^A, is operated thereby and the valve 49 is opened and as the link is moved 20 in the direction of the arrow 63'' the valve is closed. The lever 57, in this movement, moves radially from 60 to 61 and the lever 52 moves from the position indicated by the solid drawing in Fig. 38 to the dotted line 62, 25 indicating the oscillation of the valve lever 52. This valve-opening movement is accomplished by the action of the spring 63. This spring is fixed to the movable bar 58 at one end, being held by the projection thereon 58', 30 and at the other end the said spring is fixed to the rigid bar 58''. Now as the bar 58 moves in the direction of the arrow 58''' the link 54 moves in the direction of the arrow 54''' and the valve 51 is opened. The water will then 35 flow thru the conductor 48 to the spraying chamber 45 and on the sugar on the basket wall. The pin 67 on the lever 66 holds the bar 58 in the valve-closing position shown in Figs. 38 and 39, but the moment that this pin 40 is removed from engagement with the said bar the spring 63 will snap the bar 58 from i to i', which opens the valve. This lever 66 is oscillated from the said pin 67 by the automatic controller C and specially by the dog 64 45 carried thereby. See Figs. 18, 19, 20 and 21, also 22. This dog 64, it will be noted, is a pendant and pivoted one. Moving forward it maintains a vertical position, but moving rearward it will swing over the upward extending arm of the bell-crank lever 66. 50 59 is a stop on the bar 58'' to limit and predetermine the movement of the bar 58. The spring 63 pulls the bar 58 back against this stop to open the valve 51. In closing the 55 valve the dog 64 on the controller C contacts with the dog 64' and the latter is moved in the direction of the arrow 63' and the link 54, on the bell crank lever 57 is moved in the direction of the arrow 63'', which movement 60 closed the said valve. It will be noted that the dog 64', Fig. 37, is fixed to the adjustable support therefor 64'' and the holes in 64'' provide for exact adjustment for valve closing. 65 The bar 58'' is rigidly bolted to the bed plate B, as shown. I can adjust the volume of waterflow and the time of the flow by varying the position of the dog 64' on its supporting bar 64'' and vary the position of the stop 59, if I desire. 66'' are two lateral guide 70 and retaining plates for the dog carrier 64''. On the inner plate the dog 66 is carried and on the outer the cam 35'. This cam can be adjusted so as to shorten or lengthen the travel of the dog 64', before it reaches its 75 tripping position at the line f. As before explained the holes H, H, H are for adjusting the dog holder 64''. They correspond in pitch to the holes J, J in the cam plate 35', Fig. 35. The thumb nuts T, Figs. 36 and 37, are designed for quick, manual adjustment. The spring 66', Fig. 38, snaps the dog 66 in the position shown in Fig. 39 when the said dog is released by the dog 64 of the controller C. This dog 64 of the controller moves forward on line a, Figs. 37 and 39 and the dog 64', pivotally held on its adjustable support 64'', normally slides on the top of the cam plate 35' until the dog 64' strikes the position indicated by the line f which on 80 further movement, as f', the dog 64' will slide down the inclined face of the said cam plate to horizontal line a''. This will release the engagement of the dog 64, carried by the controller C, as explained, from dog 64', and the dog can travel further, if desired, and if adjustments call for it. The radial line 65 shows oscillation of the bell crank lever 66 before release from pin 67. 85

Line CL, Fig. 47, indicates the inner circumference of the curb ring, unto which ring the spray holder is pivoted at 48''. R indicates the radius of the open curb top. In Fig. 47 I show a plan of the sprayer as mounted on the top of the curb of the machine. This consists of a holder 48', having a series of adjusting holes 48''' and a clamping pivot pin engageable in any of the said holes as a locking means to hold the spray in any adjusted position. The pin passing thru the sprayer body locks it to the top of the curb. The radial and pivotal movement possible for the sprayer, in adjustment, is shown by lines Y and Y', Fig. 1 and lines YC and YC' 100 in Fig. 33. I can, therefore, swing the sprayer 45 vertically and horizontally and cover every part of the sugar on the basket wall and vary the volume and pressure of flow to any practical need. 105

110

115

120

125

130

135

Slow speed mechanism

Fig. 6 shows a plan of the slow speed drive, indicated in Figs. 1 and 4. 71 and 72 are bearings for shaft 70'. These bearings can be integral parts of the secondary bed plate B2, as shown. They can also be bolted thereto. The sleeve 70 carries sprocket wheels 73 and 74. 74 is the drive sprocket for the shaft 70' and 73 is the drive sprocket for the prime shaft 74'. The sprocket wheel 74 is

driven by the slow speed independent motor, of any class or type, by a sprocket chain which is not shown. The driving motor is also not shown, as I do not limit myself to any specific means for this drive. A chain connects sprocket 73 with sprocket 73' and the latter is keyed to the prime shaft and operates it.

75 is a jaw clutch driving member and 10 75' is its driven member, e is a collar holding jaw 75 in place on the sleeve 70. See Fig. 6. The sleeve 70, therefore carries the collar e, clutch jaw 75 and sprocket wheels 73 and 15 74 beyond the bearing 71. Sleeve 70 is in continual rotation at a fixed speed. The jaw 75 of the clutch is in continuous rotation at the same speed and it is keyed to the sleeve. The sleeve 70 is not keyed to the shaft 70' but rotates freely thereon. Jaw 75' is keyed to 20 the shaft 70' by key 70''. This jaw is an integral part of the sleeve which carries the spring 76. This spring holds jaws 75' and 75 in continual engagement while there is no force to drive the shaft 70' other than the 25 clutch jaw 75, and the speed of 75 is the speed of 75', if such force did exist. Now, it will be seen, that the sprocket 73, sleeve 70' and jaw 75 are all normally operatively connected and operate at the same time. It will 30 also be seen that sprocket 74, shaft 70' and jaw 75' are also connected and rotate at the same time. These members are all in continuous rotation and operate at the same time. They are operated by an independent driving 35 motor or means which I do not show in the drawings, not being necessary. Now to recapitulate: 75 is the driver for 75' and 75' operates shaft 70', thru key 70'' of the jaw member 75. Now if the jaw member 75' moves faster rotatively than its driver member 75 it will not rotate 75, but slip over and pass it. The spring 76 will control the snapping past and the reciprocal movement 40 of the jaw member.

77 is a pinion on the shaft 70' and this pinion drives the gear 78, which is carried on the sleeve 79 loosely. This sleeve carries a friction disc of a friction clutch 80. This friction disc is tight on the said sleeve. A 45 friction ring 81 surrounds the said disc 80. An oscillating pin 82 and a radial pin 83 in the said oscillating pin pulls the separated ends of the friction ring together, or towards each other, and whereby the ring 81 and the disc become frictionally engaged and are a friction clutch. When the disc and the ring are so engaged they have the same speed. 50 84 is the motor shaft which drives the centrifugal basket. The basket motor drives nothing else but the basket thru this shaft 84. The sleeve 79 is keyed to the motor shaft (Fig. 1) and, therefore, it rotates the same speed as the motor: gear 78 may also rotate at the same speed as the motor but only 55 when the clutch connected with the gear 78

is so engaged. At all other times the gear 78 rotates idly on the sleeve and is operated only by the pinion 77 and by the means set out.

S is a clutch spool, Figs. 1 and 5 and it is reciprocatable on the sleeve 79, or on the 70 shaft 84, if for any reason I did not wish to extend the sleeve thru the said spool. This spool is operated by the rock shaft 89 and lever 88 thereon, and thru link 87 and clevis lever 86. The only function of this 75 spool is to lock the friction ring 81 to the disc 80.

While I show the sleeve 79 on the shaft 84, I wish it known that I could dispense with this sleeve. If used, the key 85 would have 80 to pass thru the sleeve into the disc 80 so the said disc is at all times locked to the shaft 84 (see Figs. 4 and 48). In Fig. 48 the clutch for slow speed is best shown, the showing calls for the disc 80 to be free from the 85 friction ring 81. This leaves the disc 80, which is at all times keyed to the shaft 84, free to rotate at the high speed, but when I move the lever S' to the high part of the spool S''' of the spool S, Fig. 49, the projecting end O of the friction ring 81 is pulled towards O' and to the position indicated at line O' which movement will frictionally engage the ring 81 with the disc 80 and lock the disk and ring to the shaft 84. The link 90 p'' which is provided with a tapered hole p⁴ into which pin 83 enters, and the oscillation of the lever S' from V to V', Fig. 49, will move the end O of the friction ring to line 95 O', Fig. 29, which will lock the friction ring 100 81 to the disc 80 and directly to the basket shaft 84. The link p'' is held in position on the rod 82 and it reciprocates on the said rod by virtue of the oblong hole with which it is provided. The pin p⁶ is either threaded into 105 or pinned to the body of the link p⁴ and the nut p⁵ on this pin holds it taut against the projection O of the ring 80. This pin p⁶ is free enough in the hole of the extension O of the ring 80 to permit of a slight oscillation. When the arm S' is in the position shown in Fig. 48 the ring and disc 80 and 81 respectively are separated and the basket is at high speed, when the arm S is in the position shown in Fig. 49 the speed of the basket 110 is slow and the cleaner is in action thru the associated mechanism.

The rock shaft 89 is controlled by the controller C, presently to be explained and by cam 90 on the shaft 91. It is evident that when the clutch jaws 75 and 75' are engaged and operated by the driving sprocket 74, the gear 78 is rotating under the influence of the gear 77, and the disc of the clutch 80 is disengaged from its co-acting sleeve. See 120 Figs. 1, 4 and 6. I can use any type of clutch on the motor shaft. I show a standard type that is well suited for the work. I have used a magnetic clutch with much success. When the motor for high speed is dis- 125 130

connected from the basket shaft and the basket is running from momentum only and alone it may happen that the speed of the basket is greater than that given it by the shaft 70', at normal slow speed, thru gears 77 and 78. In this case the jaw 75' of the clutch would rotate faster than the shaft 70', on which it is carried. The inclined face e' of the jaw of the clutch 75' will, in this case, 10 pass over e'' of the clutch 75, but not rotate e'' , and the spring 76 would keep the jaws in continual engagement until the momentum of the basket was sufficiently arrested so that the basket has a speed as slow as that given it by the shaft 70', at the normal slow speed.

The object of the mechanism just described is to prevent accident and to save the mechanism against smash in case the predetermined slow speed of the basket is not down to the proper rotation when the lever 86, thru the means described, has connected up the disc 80 with the ring 81 frictionally. I will now describe the mechanism that controls the rock shaft 89 and

The positive control of the slow speed

First: The law of my machine requires that the high speed for purging takes place in a certain number of the degrees of the machine cycle, and, following this, the motor, of whatever class, must become disconnected from the basket and the basket momentum then becomes the sole driving force. This force must be overcome speedily, so as to bring down the speed of the basket from the high speed to the predetermined slow speed within a certain and limited time. At the slow speed the basket will be connected up with the slow speed driving mechanism, at which time the basket will be cleaned of the separated solids hanging on its inner wall. The basket during the operation of cleaning, or unloading, must not be operated by momentum, as it is too unreliable, and a fixed predetermined speed is the requirement for a practical machine. It may sometimes occur that the basket will almost stop, or entirely so, for a moment before the slow speed mechanism is connected up, but this is not material and will not in any manner interfere with the picking up of the speed to the predetermined slow.

In Fig. 18 I show a side view of the cycle controller C. The shaft 74' is the prime shaft of the machine. In Fig. 18 this shaft is shown as divested of all associated members. This shaft is in continual rotation, being driven by the sprocket wheel 73' which it carries, and this wheel is driven by the sprocket 73 of the shaft 70', carrying sleeve 70. 92 is pinion on the shaft 74' and 93 is a spur gear driven by this pinion. 95 is lead screw which carries the automatic mechanical controller C. This lead screw is in continual rotation.

96 is a dog lock carried by the controller and its function is to lock the controller to the lead screw. 98 is a stop trip for this lock. In Fig. 21 I show this dog lock as out of locking engagement with the dog 100. In Figs. 20 and 23 I show it in locking engagement with the said dog. This dog lock consists of a cam shaped head d , a throat d' and a thrust end d''' , into which the end of the throat is threaded, thus making it adjustable. Now as the lead screw 95 rotates, the controller C is carried in the direction of the arrow b^2 , Fig. 18, until the dog lock 96 and d''' engage the end of the thrust rod 98, carried by the standard S1. While this movement is on the position of the dog lock is as shown in Fig. 20, where the head of the dog lock is over the dog 100. This holds the said dog engaged with the lead screw 95. On further movement, as the pin 98 is fixed against movement, the dog lock will be forced back against the spring d'' and away from the vertical path of the dog 100. The spring ST will then force the dog 100 out of the teeth of the lead screw and against the pin 97 which arrests the movement. See Figs. 18, 19 and 23. The controller C is now disengaged from the lead screw and it is free to move rearward in the direction of the arrow C2, Fig. 18, and this movement is controlled and continued by the weight 104 on the chain 103 fixed to the said controller and pulling it rearward until the dog 100 strikes the cam 102, when the arm of the said dog engages with and slides on the said cam from line K' to K, Fig. 18. Now as the lead screw 95 is in continuous rotation the said dog will immediately engage in the annular channels of the lead screw, whereupon the spring d'' will snap the dog head d over the dog 10 and the dog is now again locked to the said lead screw, and so remains until the cycle is completed and, at which time, it again becomes unlocked in the manner described. The controller C is carried forward, to recapitulate, in the direction of the arrow B^2 by the lead screw and rearward by the weight 104 on the chain 103, Figs. 1 and 19, once in each cycle of the machine, it is the primary control for all the automatic features of the machine, which I will now describe functionally.

In Figs. 5 and 18 radial lines are projected from the center of the rock shaft 89. Line F indicates high speed for motor and basket, N indicates a neutral position, or that the basket is running on momentum alone and S indicates the slow speed, or that the slow speed motor alone is driving the basket and that the high speed motor is dead. 105, Figs. 1, 4 and 18 is a lever on the rock shaft 89. This is the actuating lever therefor. This is the actuating lever and shown best in Fig. 18. The thrust rod 99 is pivoted to this lever. In its oscillation from F to N this lever is controlled by the controller C thru the

thrust pin 97 thereon engaging thrust pin 99 of the rock shaft 89, which latter it oscillates from F to N, or from high speed to neutral position. It does this at the end of each cycle 5 and just prior to the unlocking of the controller from the lead screw as follows: as the neutral position N of the lever 105 is reached the parts are so adjusted that the dog lock 96, thru and by its head d'', engages the thrust 10 pin 98 which is stationary in the standard, it will be remembered, and moves it to a degree sufficient to force the end from the position shown in Fig. 20 to that shown in Fig. 21, or from Y' to X' and immediately the spring 15 ST, Figs. 20 and 23, will snap the dog 100 out of the annular groove of the lead screw to the position shown in Fig. 21, or from line 12 to line 13, Fig. 23, after which the chain 103 thru weight 104 pulls the controller C in the 20 direction of the arrow C2 until the dog 100 strikes the cam 102 at K and reengages the lever 100 with the lead screw, and a succeeding cycle is commenced. In Figs. 4 and 5 I show a link 106A connected with a rack 107 25 and lever 107' on the rock shaft 89. This lever is on the same radial plane as the lever 105. The rack 107 has teeth removed, as shown in Fig. 5 and when these teeth, as shown in the figure, are disengaged from the 30 pinion 108A, of the controller 109 the high speed motor is dead. In Fig. 5 the radial lines F, N and S indicate the same rotative values and functions as in Figs. 1, 4 and 18, so that when the rack is at S the slow speed 35 drive is operating the basket. This is accomplished by the lever 88, thru link 87 and lever 86 forcing the clutch spool S down, and thru lever S' oscillating pin 83 in shaft 82 from line P' to P. Link pin P'', in this movement, pulls the separated ends thru their radially projecting arms O' and O'' towards each other and causing arm S1 to ride on the high part of the spool S in which position the clutch is locked, and so the disc 80, which 40 is rotating with the sleeve 79 becomes frictionally locked with the latter and the high speed motor while dead, is now rotated by the slow speed drive, merely because they are connected with a common transmission 45 for the basket, but have individual drives to this transmission. At this time, as is evident, all the work is being done by the slow speed drive. I do not limit myself for basket drive at either high or slow speed. It may be belt, 50 water, steam. I have now described how the controller C becomes locked and unlocked from the operating lead screw 95 and how it operates, thru lever 107', the rock shaft 89, link 106A and rack 107, the controller for the 55 high speed motor and cutting off the current thereof. I have also fully described how, at this time, the only driving force for the basket is the momentum thereof. This momentum I must overcome quickly. 60 Sleeve 107''', carried by the prime shaft 65 74', Figs. 6 and 19, carries a worm 108 and a clutch jaw 109. This sleeve is not fixed to the said prime shaft, so the shaft is free to rotate while the sleeve is stationary. 110 is a brake, best shown in Figs. 1, 3 and 19. The function of this brake is to arrest momentum and quickly stop the sleeve and the worm 108 and clutch jaw 109 when the jaw 109 is released from jaw 113. The engagement of the clutch jaw 113 with the jaw 109 is accomplished as follows: the jaw 113 oscillates on its pivot pin p''' of the sleeve 114. A groove 116 on the said sleeve holds the said jaw 113 within fixed limits, lateral springs 117 and 118 permit the dog to oscillate in either direction from a longitudinal line thru the pin p''', forming the pivot for the jaw 113. The sleeve 114 carries an annular groove 115. This sleeve is keyed to the shaft 74', see Figs. 19 and 44. The pins 119 of the sleeve move 80 clevis 129. The said clevis moves slowly, but the clutch jaws must engage quickly, which they could not do if moved by the clevis as a lever. I therefore give these jaws a quick longitudinal movement as follows: 85 Fig. 42 shows a link 134 for disengaging clutch pin 113 thru the movement of the supporting sleeve 114. The clevis is pivoted at 127 to a support therefor 128 which is carried by the bed plate B. 135' is a lever pivoted at 131 to the standard S2 and 132 is a link connecting lever 135' with the clevis. The dog 120 slides on pins 122 on the link bar 134, a slot thru the dog permitting this reciprocal movement of the dog. 135 is a link carrying pin 124, a spring 126 pulls this latter link in the direction of the arrow A A, Fig. 42. Normally a slot, Fig. 41, only permits this link to slide on pin 136. This pin is threaded into the clevis 129. The pin 123 90 on the link 135 is adjustable thereon. The controller C is shown in Fig. 19 in its assembled position with respect to the links just described and the prime shaft. This controller carries a lug 137 to which chain pull 103 is attached for rearward motion of the 95 said controller, as has been already set out. 100 135 is a pinion on the prime shaft 74' and 99 is a spur gear on the lead screw. The pinion is the driver and the spur gear is the driven gear. The lead screw carries and drives the controller C. The lug 137 of the controller contacts with the pin 123 as the controller moves forward. This pin is on the link 135 and at this contact the link will 110 also move. Now it will be seen that the clevis, Fig. 42, has an inclined face towards the pivotal center thereof. The purpose of this inclination is to avoid nice adjustment, so, as the link 135' is moved forward the pin 124 moves away from the radial limits of the cam face 129, and, when so moved the spring 139 on the prime shaft, will snap the clutch 115 jaws 113 and 109 quickly together. q and q' 120 in Fig. 6 and lines T and T' in Fig. 42 show 125 130

the movement of the pin 124 before it becomes disengaged from the cam face 129 of the clevis. The movement of the clevis will be from T to X' or X' to T' depending 5 on how much the clevis was moved previously. The worm wheel 140 rotates when the clutch jaws 109 and 113 are engaged, Fig. 42. The worm wheel 140 makes one complete revolution in each machine cycle. This 10 wheel carries two trip pins 141 and 142. Pin 141 is the pin which operates the lever link 134 by engaging the dog 120, or a movement equal to the movement indicated a^2 to a^3 , Fig. 42, at which conclusion the wheel 140 15 will stop. During this time the cam face of the clevis 129 will have moved away from the path of the pin 124 and the said pin will be snapped under the face 138 of the clevis by the force of the spring 126 and hold the 20 clevis in the position shown in Fig. 42 until the lug 137 of the controller C again moves the link 134 forward, as described. The end of the standard S1 has a guide slot 143A, Fig. 19, to guide and retain the link 135' in 25 a fixed position, and the spring 126 has a thumb nut 145 for adjusting tension. The spring rod 146A passes thru the standard S2. It will be understood that the passing of the pin 124 from the bottom face of 138 of the 30 clevis can never occur before the dog 120 is raised from pin 141 on the worm wheel 140. The reason that this is so is because the worm wheel 140 is locked to a fixed position when the dog 120 is locked against the pin 141, 35 then the link 134, lever 135' and link 132 hold the clevis 129 in a position to clutch disengagement. All the parts: wheel 140, dog 120, worm 108, link 134 which carried dog 120 and link 132 which holds clevis will be 40 in rigid engagement and so remain as long as the dog 120 is in tight engagement with the pin 141 of the worm wheel 140. But the moment the trip lever 147, (see Figs. 42 and 45), raises the dog 120 beyond the path of 45 the pin 141, the spring 121 will snap the dog 120 over the said pin and on the top thereof, as shown in Fig. 46. The clutch jaws are disengaged and the parts are free until the movement of the controller C on its lead 50 screw thru lug 137 on the said controller, on its forward movement, strikes the pin 123 on the link 135 and moves the pin 124 from under the lower face 138 of the clevis 129 when the clutch jaws 9 and 13 will be en- 55 gaged by the spring 139 and the worm 108 will be thus locked to the prime shaft and the worm wheel 140 in the succeeding cycle. So the pin 124 is always under the clevis 129 when the clutch jaws 13 and 9 are disengaged and the said pin is always disengaged from the said clevis when the worm 108 is in action. The sliding movement, or slack, 60 of the dog 120 is to snap the dog over the pin 141 by the spring 121 when the lever 144 raises the link 134 sufficient to disengage 65

the dog 120 from the pin 141. After the dog is snapped over on the top of the pin 141 it remains there until the worm wheel 140 is again rotated in the succeeding machine cycle. 70

The springs 117 and 118, on jaw 113 of the clutch sleeve 114, permit this jaw to swing to the right or the left when the jaws are engaging and this insures a positive engagement. 75

Assuming that the members 109 and 113 are not in engagement with each other, the basket is connected to the high speed motor and the controller is moving in the direction of the arrow b^2 . In the course of its travels 80 in this direction member 97 of controller C connects with the thrust rod 99 shifting lever 105 from F to N (or fast speed position or neutral position). This causes lever 147 to raise link 134 so that the dog 120 clears the pin 141 on the worm wheel 140. Simultaneously with this movement lug 137 on controller C contacts with the lug 123 on link 135 and shifts the same in the direction of the arrow b^2 . This causes the pin 124 to move beyond the under surface 138 of the clevis 129 and the spring 139 then moves the sleeve 114 forward so that the clutch member 113 engages clutch member 109. The prime shaft 95 74' then transmits power thru the sleeve 100 107''' by means of worm 108 to the worm wheel 140 which rotates in a clockwise direction regarding Fig. 42. Since dog 120 has been carried above pin 141, as previously pointed out, by means of lever 147 raising link 134 this pin 141 passes beneath the dog 120, as shown in Fig. 46. By this time the controller C has returned in the direction of the arrow C^2 due to the contact of the dog lock d''' with member 98, and lug 137 of the controller C has been removed from contact 105 with the lug 123, and link 135 moves back in the direction of the arrow C^2 under the influence of spring 126 until pin 124 contacts with the upper curved surface of the clevis 129. 110

As the worm wheel 140 continues to rotate the brake mechanism is applied and the apparatus is shifted to slow speed position by means of the cam wheel 90 as clearly explained in a later portion of this specification. 115 Now, as the worm wheel 140 continues to rotate, the pin 142 contacts with the lug 146 and thru link 145 and lever 144 (Fig. 42) until it is at position F and the mechanism is in high speed position. This causes lever 147 to lower link 134 and the dog 120 is again in the path of pin 141 and when pin 141 contacts with dog 120 it moves lever 134 forwardly and throws clutch member 113 out of engagement with member 109, simultaneously with this clevis 129 is oscillated in a counter-clockwise direction on pivot 127 and pin 124 on lever 135 rides on the upper curved surface 120 thereof until it comes to the end when it will 125 130

snap back beneath the clevis which brings the mechanism to its initial position.

I have now described how the controller C engages the clutch on the prime shaft and disengages it. I will now detail the mechanism controlled by the worm wheel 140. 89 is a rock shaft carrying two levers 144 and 147. These levers can be single or compounded (as shown) Fig. 45 in plan and 42 in assembly. 143 is a parallel lever to 144. The link 145 holds the levers in radial parallelism and connects them. The lug 146 is carried by the link 145 at its lower end. As explained the link 134 is the unlocking link for the clutch jaws 113 and 109. The link 134 rests on the upper side of lever 147, best shown in Figs. 45 and 42. In Fig. 42 the parts 143, 144, 145 and 146 are shown in the neutral position of their functioning. N, Fig. 42, 148, dotted line 20 shows the position of the arm 143 at slow speed, line 149 the position at high speed, F. Now when the controller C, thru the thrust pin 97, which it carries, contacts with the movable thrust rod 99 the latter will be moved 25 and, as this rod is pivoted to the lever 105 and the latter is keyed to the rock shaft 89, the rock shaft will oscillate from line F to line N, or from high speed position to neutral, as I have fully explained previously. The motor 30 for high speed becomes dead at this time. The link 106A on lever 107' controls the electrical control rack 107 for this function.

The cam 90, Fig. 15, is on the cam shaft 91 and normally rests in the position shown in this figure. Now after the rock shaft 89 is oscillated and the lever 147, on which the link 134 rests, being oscillated with it, the said lever raises the dog 120 carried thereon until the said dog takes the position shown in Fig. 46 and rests on the top of the pin. Now, it will be remembered, that the function of the link 134, thru lever 135' and link 132, is to unlock the clutch jaws 113 and 109 and oscillate the clevis until the pin 124 passes under the inclined end 138 thereof, which pin 124 holds the said clutch jaws open until the link 135, on which the pin 124 is carried, is moved forward in the next preceding cycle. Meanwhile, as the pin 141 on the worm wheel 50 140 is under the dog 120, the link 134 is free to move as soon as the pin 124 is out of the path of the clevis end 129, when the clutch jaws 113 and 109 will be free to engage and the worm wheel 140 is again in position to rotate.

As the said worm wheel rotates the cam 90, being on the same shaft 91, will rotate with it in the direction of the arrow 151, Fig. 15. The brake lever 152 will then drop and the roller 158 will rest and roll on the smaller circumference of the said cam 90. The springs 159 and 159' will now be free to pull the arms 161 towards each other as their expanding cam 162 moves down with the rod 157 to which it is attached. The brake shoes 163 and 164, thru their linings 180 will impinge

the brake wheel 165 and the basket shaft, which carries the brake wheel, will be quickly brought down to a slow speed. The link 153', Fig. 15, has two lateral integral members 153' which form in effect a bridge. A pin 155A holds the link to the shaft 157. At its lower end two pins 154 pivotally hold this link to the lever 152. The lever itself is pivoted to the holder therefor 170 on the bed plate B. Now while the cam 90 is rotating from W to W' the brake cam 162 is down and the brakes are arresting the momentum of the basket. When the roller 158 has rolled up on the wall 172 of this cam and it is at the high point 172', the pin 171, on the cam 90, will have reached the position 172'' and, in this position, it contacts with the lever 106 at Z. This lever will then be oscillated to radial line 173, during which oscillation the pin 171 will have moved to radial line 174, at which point the pin moves on but the lever 106 stops. The link 175, which connects lever 106 with the lever 176, moves the latter from the neutral, N, position to S or slow speed position. During the neutral position momentum alone operates the basket until slow speed is accomplished. At this speed I clean the solids from the rotating basket wall.

In Figs. 30 and 31 I show plan and side views respectively of the brake arms 161. They are bolted to the bed plate B2 by bolts 181'. The shaft 85 carries the brake wheel 165. Brake adjusting screws 161'' are carried by the arms 161. The distance indicated by the line 177 is the extreme limit of arm expansion and line 178 the minimum. 163 and 164 are asbestos brake linings. In Fig. 15 dotted lines W4 and W5 indicate the terminals of the cams W6 and W7 and the arms 160 and 161, the latter being part of the former.

Arrow 9W shows the direction in which worm wheel 140 rotates. After the dog 120 is raised by the raising of the link 134 which carries it. Thru raising of the link 134, and thus bringing the pin 141 under the dog 120 the worm wheel becoming unlocked is free to rotate. The pin 141 is on the inner side of the worm wheel and the pin 142 is on the outer side thereof. In stopping the worm wheel 140 the pin 142 will engage the lug 146 of the pendant link 145 at the radial position 148 for the lever 143. It will pull the lug down until the lever 143 occupies the position shown by the dotted line 149 from pivot pin 149'. The pin 142 on the worm wheel will then be released from its contact with the top of the lug 146 at the intersection of the lines 149 and W7 and the worm wheel will continue to rotate until the said pin reaches the point indicated by the line W8, at which point the mechanism is adjusted to stop by unlocking the prime shaft clutch jaws 113 and 109, as set out. So when the pin

142 has moved to line W8. Pin 141 is under the dog 120 as shown in Fig. 46. During this movement, the lever 105, Fig. 18, has moved from N to F reseating the thrust rod 99 to its normal position and the lever 88 has moved to line 88', Fig. 4, and thru link 87, lever 86 the friction ring 81 of the friction clutch is released from engagement with its disc 80, and the rack 107, thru 106A and lever 107', latter on shaft 89, has put the controller on its contact for high speed motor drive. The basket will now be free to rotate at high speed, F. The worm wheel 140 will be at rest, as well as the rock shaft 89 and all its connections. The controller C, however, is traveling on the lead screw 95 and will so continue until the thrust rod 97 is again in contact with rod 99 when the rock shaft 89 will be again oscillated from F to N and all the operations repeated and so on successively and continuously.

Cleaning of the basket

This I accomplish as follows: Fig. 8 shows a type of cleaner used or usable. It consists of an upper sheet 180, a lower sheet 181, a deflector 184. These sheets can carry fiber tips O, O, O, O, which can sweep the basket shell. 186 is a supporting shaft for the support of the sheets aforesaid, and 187 a bearing for the shaft on the top of the curb 44. 189 is an open space between the two sheets named. 188 is a lug which supports the plate 180A to the shaft 186. The spreader 193 is a circular disc having a tapered curvilinear boss and held to the basket shaft 27. It is directly over the basket bottom indicated by line 194. 191 shows the position of the cleaner when the basket is at slow speed, S. 195 is a union collar uniting shaft 186 with shaft 197. These two shafts show separation at 198. 196 is an integral segmental pinion carried by the collar 195. 198 is a spring on the rod 199 and 200 is a compression for the said spring. 201, Fig. 6 is the arm of a segmental rack operating the segment pinion 196. 202 and 203 are radial lines indicating oscillatable limits for the said rack. This rack is pivoted to the under side of the bed plate B (not shown). 205 is a loose collar and 204 is a nut threaded to the rod 199. As pressure is applied to the rod 199 the collar 205 thru the spring 198 will force the rack arm 202 in the direction of the arrow 207. This will oscillate the shaft 197 in the direction of the arrow 208' and the cleaner 180A from WO' to WO, Fig. 6. This movement corresponds to the movement of the cleaner from radial line 190 to line 191, in which latter position the wall B''' of the basket will be cleaned of impacted material after being purged of its associated liquid. The basket rotates in the direction of the arrow 208'. The cleaner is gradually oscillated towards the basket wall, or from WO' to WO

and will shave the sugar of the mass hanging on the basket wall in small sections until the wall is reached when it becomes static for a little time, during which operation the sugar is conducted centripetally to and thru the basket bottom. The cam 208, which is fixed to and operated by the shaft 91, Fig. 7, with its rise R forces the cleaner against the wall, the section R' holds the cleaner there for a short time, the section R2 quickly returns the said cleaner to its normal position, where it is held by the section R3 while the basket is being filled and the fill-mass is being purged and at the high speed. The hole in the segmental arm 201 for the passing of the shaft 80 is larger than this shaft, the collar 205 is free on the shaft 199 and when the basket shaft and basket wall oscillates variably this permits the cleaner to hub the said wall regardless of such oscillation. The spring 198 communicates the thrust of the spring 198 to the arm 201 and therethru to the scraper, which is in contact with the separated material hanging on the basket wall, during the cleaning operation. As the shaft 199 pulls the scraper 180A away from the basket wall it is desirable to raise the cleaner off the basket bottom for safety, at speed. This is accomplished by the roller 211A rolling on cam 209, the roller being carried by the arm 210 fixed to the shaft 197. In Fig. 4 I show a basket bottom in combination with the said spreader, also a detail of the construction in Fig. 9. This arrangement prevents the accidental passing of the solids at the wrong time. The cleaner used is the same as that described, but the basket bottom must have a greater lift than the cleaner to permit the separated mass to pass quickly by centripetal action, forced by the static cleaner carrying the material to the port in the bottom of the basket B''', 211 is the basket bottom valve, which seats in B''' when closed. This bottom is carried on the sleeve 213. The spreader 193 is carried on the same sleeve. The sleeves carries a lifting collar 214 which is raised by the clevis 217 on the lever 215. Radial line, Fig. 4, 218 shows the upward lift of the arm 215, and line 219 shows the downward position of the said arm. In the latter position the spreader 193 is at the position indicated by the numeral 212, Fig. 4, and the bottom is resting in its seat B'''. The space 189 formed by the separated cleaner sheets 180A and 181 is of a size to permit the spreader 193 to vertically reciprocate therein, as shown. The arrow 226 shows the rotation of the cam 225, which cam is carried by the shaft 91. The arrow 227 shows the rotation of the cam 90 carried by the same shaft. 220 is a link connecting the lever with bell-crank lever 222-223. The cam 225 is so adjusted that when the roller 230, Fig. 32, is on the high part thereof the cleaner is scraping the basket wall and the speed is slow. Line n represents

the position of the lever 224 when the lever 215 is raised and line M the position when the bottom 212 is closed and the spreader is down the cam 225 is operated by the shaft 91.

Feeding the basket

In Fig. 11 I show the lower part of a mixing chamber 234, such as is used in sugar mills. 233 is a spout with a gate 237 and a gate seat 238. The gate seat is the end of the said spout 238'. The gate is pivoted to the said seat by a resilient pivot pin 244, Fig. 12. The resiliency is caused by a compression spring 246 and adjusting nuts 245. The contact between the gate and its seat must be liquid tight. 236 is a lifting link carried loosely in the guide 235 on its upper end and on its lower bolted to the gate lifter 242, as shown. The dotted line 241 indicates the position of the lifting link 236, which is held to the gate 237 by the pin 246. The guide 235 for the bar 236 can be of varied design. A, A1, A2, A3 are a series of pin holes for the pin 246. This pin is held by a lifter 242 and is engageable in any of the said holes. These holes are intended to meet variable conditions for feeding the basket by making it possible to open the gate to a greater or less degree. This is indicated by lines A, A1, A2 and A3, where A is the shortest lift and A3 the longest, but the time of the gate opening is the same, as any one of the pin holes will release the pin at the line 243, or when the roller 247 passes from under the dog trip 240 at the intersection of the line, the circumferential line 239, after which the gate 237 will drop by gravity to the position shown in Fig. 14, and the flow of fillmass to the basket will be arrested. I can increase the time of opening the gate by lowering the dog 240 in any one of the holes L on the bar 236 and reduce the time by lifting the said dog on the said bar. Fig. 13 shows an anti-noise and thrust arresting seat for the gate 237. It consists of hard rubber 251 and soft rubber laminations 252 and a common pin 253 to hold these parts to the lug 238'' of the gate holder 238'. The shaft 91, which is the main cam shaft of the machine carries a lever 241 which supports the roller aforementioned. This cam shaft is directly operated by the worm wheel 140 as they are on the same shaft. The feed gate 237, shown also in Figs. 1 and 7 is entirely controlled by the arm 241. The operation of the feeding mechanism is as follows: We will assume that the machine is employed for sugar and will assume further that feed gate 237 is closed, as is shown in Figs. 1, 7 and 11, the basket is loaded for a purge with and the controller C is adjusted for a time suited to the material, the worm wheel 140 is at rest on the shaft 91, the cam shaft of the machine and the dog 240 (Fig. 11) resting at its adjusted position, the idle period of ad-

justed position for the controller is about over and the pin 97 on the controller C is about to engage the rod 99 on the lever arm 105 with this lever arm at the high speed position, or F. This arm 105 will be oscillated from F, or high speed position, to N or the neutral position, this will oscillate shaft 89, with which arm 105 is rigid, and also lever 107, the latter raising link 135 carrying dog 120 until the said dog slides on the top of the pin 141 carried by the worm wheel 140. It will be understood that the dog 120 is in the path of the pin 141 at the time of this contact. Synchronously with the movement described the pin 123 of the link 135 will have moved forward in the direction of the arrow b^2 , Fig. 18, until, it will have passed the point Q' of the clevis 129, Fig. 42, whereupon the spring 139 will immediately cause the engagement of the clutch jaw 113 with jaw 109 and the worm wheel 140, thru worm 108 of the clutch jaw 109, will then rotate in the direction of the arrow 9^w, as previously set out.

During the period of high speed rotation 90 the brake lever 152 (Fig. 15) rests on the cam 90 of the shaft 91, as shown, but the moment 95 the jaws of the clutch 113 and 109 are engaged the worm wheel 140, shaft 91 and cam 90 will all rotate uniformly, being all connected. The lever 241, however, which is on 100 the same shaft 91 and which opens the feed gate 237 is so adjusted on the said shaft that it will not engage with the dog 248 until the basket is cleaned of separated solids and the 105 parts returned to normal position.

As stated the cam 90 is in the position shown in Fig. 15 when the action of the controller C starts this cam rotating on its shaft 91 in the direction of the arrow 151. 105

As the cam 90 rotates from W' to W the roller 158 on the lever 152 drops on the low part 156 of the said cam and this allows the rod 157 to drop and the springs 159 and 159' to apply the brakes to the brake wheel 165, (Fig. 30). The tension of these springs can be adjusted by the thumb nuts with which they are provided, and must be so adjusted as to bring down the speed of the basket quickly. The brake wheel 165 is keyed to the basket shaft 85 shown in Fig. 4. As the speed of the basket gets down the link 221 on the cam 228 (shown best in Fig. 32) will raise the basket bottom thru bell crank lever 222, link 220, lever 215 and sleeve 213 to the position shown at 211, Fig. 4. While the basket bottom is raised, as stated, the unloader, or cleaner rod 186, is oscillated to the basket wall. This is accomplished by the segmental rack 196, an integral part of the shaft union 198, rack 201, link 199, cam 208 on the shaft 91 and the cam roller supporting arm 209' (see Figs. 4, 6, 7, and 10). As the unloader blade 180A (Fig. 4) contacts with the basket wall, on the oscillation of the shaft 120

which supports it 186, it engages the separated solids hanging thereon and removes them centripetally to the open basket bottom or between the space 211 and B'/' which is the open space between the raised bottom and its seat on the top of the basket. After the solids are removed from the basket wall, as set out, the cleaner is returned to its normal position by the same elements that have been described. The feed gate 237 then starts to open by the roller 247 on lever 241 carried by the rod 91 contacting on the under side of the dog 248, Fig. 13 and thus lifts it, thus permitting the fillmass to pass into the basket from the chamber 234 thru feed spout 233, as shown in Fig. 11. The volume of fillmass can be adjusted to any amount desired by raising or lowering the dog 240 to any one of its adjustable holes in the bar 236 which supports it, and increasing or decreasing the radial contact of the adjusting pin to the desired hole of the series shown at A1, A2, A3, or A4, Fig. 14. During the cleaning or unloading of the basket in the manner just described the lead screw 95 moves the controller C forward in the direction of the arrow b², Fig. 18. This idle travel of the controller during the period of the rotation of the worm wheel, and covering the time of unloading the basket, must be added to the time for adjustment for the cycle of the machine. The machine cycle, therefore, contemplates this idle movement of the controller C plus the time consumed by the controller traveling on the lead screw after the idle period noted thereof, plus the time to feed the basket and purge the fillmass which has passed thru the said feed gate, plus the time to unload the solids from the basket wall.

Briefly in recapitulation: The feed gate 237, following the washing of the sugar (if the machine is employed for sugar service) is closed, the material is unloaded from the basket, by opening the bottom first and after the unloading closing the basket bottom, during this time the slow speed drive operates the mechanism; after the bottom is closed the feed gate is opened and the material is passed into the basket for a time predetermined by the adjustments the feed is cut off, the high speed is arrested and after high speed is arrested, momentum drives the basket, slow speed is connected up and wheel 140 operates with its duties performed as set out.

I do not confine myself to electric motor. It may be a belt drive, steam, water or any means that will give the power suitable applied to the mechanism for its efficient operation. I could even use a single motor and give it two independent speeds and exact speed ratios, but I prefer the two independent motors as they have proven very efficient.

In no part of this machine do I limit myself to the specific structure set out, as I

could make numerous modifications without departing from the spirit of my invention.

Functional recapitulation

The feeding mechanism can be adjusted as to volume and time. There is no limitation as to the character of speed drives for either the slow or high. Following the high speed the sugar is washed, but I could make the washing intermittent, if I so elected. I do not limit myself in this regard.

I do not limit myself to specific construction in any particular, as I could make many modifications without departing from the spirit of my invention.

Having now described my invention and the manner of its working what I claim and desire to secure by Letters Patent is:

1. The combination in a centrifugal machine of a basket, a feeding mechanism including a feed regulating valve, a prime shaft in the machine, a mechanical connection between the said feed valve and the said prime shaft, adjustable means for the said valve whereby the volume of feed can be varied and regulated to meet different conditions of density and viscosity, and a controllable cleaning device, whereby material fed into the basket after the solids are separated therefrom, can be expelled.

2. The combination in a centrifugal machine of a basket, a supporting shaft therefor, a high speed motor drive, means to feed the basket at a predetermined time in the machine cycle, comprising a valve, means to open the valve, means to close the valve, means to vary the feed thru the valve, a prime shaft in the machine, a mechanical connection between the said prime shaft and the said valve operating mechanism, a slow speed drive and a cleaner adapted to clean the basket of separated solids at the slow speed.

3. The combination in a centrifugal machine of a basket having means to give the said basket a high and low speed rotation at different times in the machine cycle, means to feed the basket at a predetermined time in the machine cycle, means to predetermine a time in the machine cycle when momentum alone will rotate the basket, independent and positive means to connect the slow speed drive with the basket after momentum control has expired, a basket cleaner and means to put the cleaner in action at the slow speed, whereby the said cleaner will scrape the basket wall and remove impacted solids thereon to exit.

4. In a centrifugal machine the combination of a basket, a cleaner for the said basket, means to rotate the basket at a high speed, for a predetermined time, independent means to operate the basket at a slow speed for a predetermined time following the high speed operation, comprising a motor, a momentum arrester, a clutch on the basket shaft and a

secondary safety slip clutch interposed between the slow speed motor and the basket shaft, whereby, after the high speed of the basket period, as predetermined, has expired 5 the slow speed for cleaner action is put in service.

5. The combination in a centrifugal machine of a basket, a supporting shaft therefore, a high speed motor directly connected 10 with said basket shaft, an electrical circuit for said high speed motor, a switch in said circuit, means to open and close the said switch, a slow speed driving mechanism for the said shaft, means to connect the slow 15 speed driving mechanism with the said basket shaft when the said switch is open and the high speed motor is dead, comprising a clutch on the basket shaft and a mechanical connection between said clutch and said slow 20 speed driving mechanism, whereby the basket is rotated at slow speed when the said switch is open and the high speed motor is dead, as and for the purpose set out.

6. In a centrifugal machine the combination 25 of a basket, a basket shaft, a high speed direct connected motor for the said shaft, a switch in the high speed motor circuit, whereby the motor is controlled, means to control the switch, a slow speed driving means, a connection between the slow speed driving means 30 and the said basket shaft, consisting of clutch on the said basket shaft, one member of the said clutch fixed to the said basket shaft, a second member of the said clutch rotatively 35 connected to the slow speed driving means, and means for engaging the two clutch members to connect the slow speed driving means to the basket shaft when the switch is open.

7. The combination in a centrifugal machine 40 of a high speed motor, a basket shaft, a basket supported by said shaft, a high speed motor circuit, a switch in the said circuit, means to control the said switch, a slow speed driving means for said basket, means to connect the slow speed driving means to said 45 basket shaft at a predetermined time in the machine cycle after the said switch is open, comprising a clutch on the basket shaft, said clutch having a disc fixed to the shaft and a friction ring surrounding said disc and connected to said slow speed driving means for rotation thereby, a prime shaft in the machine, means for driving the prime shaft and a mechanical connection between the said 50 friction ring and the prime shaft, whereby the said ring is contracted by the prime shaft thru said mechanical connection and the ring is thus locked to the disc on the basket shaft, rotating the shaft at the slow speed, 55 as and for the purpose set out.

8. The combination in a centrifugal machine 60 of a basket, a basket shaft, a direct connected high speed motor for the basket shaft, means to open and close the high speed motor circuit at a predetermined time in the ma-

chine cycle, a slow speed driving means independent and positive means to connect the slow speed driving means with the basket shaft when the high speed motor circuit is open, comprising a clutch element on the basket shaft, a clutch element connected to the slow speed driving means for rotation thereby, adapted to engage the clutch element in the basket shaft, a prime shaft in the machine, driving means for the prime shaft, a mechanical connection between the prime shaft and the element of the said clutch which is connected to the slow speed driving means and adapted to engage the fixed element at the slow speed, whereby the slow speed driving means will rotate the basket at slow speed thru the said mechanical connection between the clutch on the basket shaft, and the said slow speed driving means, while the prime shaft, thru the said mechanical connection between said prime shaft and the said clutch element, which it controls, will lock the members of the said clutch together and the basket will rotate at slow speed as predetermined.

9. The combination in a centrifugal machine of a basket shaft, a high speed motor for the said basket directly connected to said basket shaft, an electrical switch to control the said high speed motor, means to open and close the said switch, a slow speed driving means for the said basket, a mechanical connection between the said slow speed driving means and the said basket shaft, comprising a clutch on the said basket shaft, a mechanical connection between said slow speed driving means and said clutch, consisting of a shaft, a driven slip clutch element on said shaft, a driving slip clutch element connected to the slow speed driving means, whereby when the basket is at high speed the clutch on the basket shaft is disengaged, and the shaft supporting the slip clutch is functionally idle, but when the high speed motor circuit is open the slip clutch of the slow speed driving means is operative and the basket is operated at the slow speed, as and for the purpose set out.

10. In a centrifugal machine the combination of a basket, a means to rotate the basket at a high speed, means to feed the basket of material to be separated, a water feed controller comprising a liquid conductor, a valve in the said conductor, means to open and close the valve at a predetermined time in the machine cycle, a spraying chamber, a conductor between the said valve and the said chamber, said spraying chamber being provided with a perforated cover, a laterally adjustable plate mounted on said perforated cover to increase or decrease a flow of water thru the perforations of the cover and an adjustable support for the said chamber, whereby the angle of liquid flow to effectually reach the basket wall can

be varied by adjusting the said chamber on its support.

11. The combination in a centrifugal machine of a basket, a basket supporting shaft, a feeding means for the basket, a cleaning means for the basket, means to rotate the basket at a high purging speed, means to control the period for the high speed, means to operate the basket at a predetermined slow speed independent of the high speed operating means, comprising in combination with the slow speed driving means, a clutch on the basket shaft, a connection between the slow speed driving means and said clutch, consisting of a shaft, a slip clutch element on said shaft, a second slip clutch element connected with the slow speed driving means, a brake on the said basket shaft, means for applying the said brake for basket speed arresting at the end of the high speed period and means for releasing the said brake at a predetermined time thereafter, as and for the purpose set out.

12. In a centrifugal machine, a basket, a basket shaft, a motor operating the basket shaft at a predetermined high speed, a slow speed shaft, an independent motor for driving the slow speed shaft, a pinion on the slow speed shaft, a gear meshing with said pinion and journalled loosely on the basket shaft, a clutch connected to said gear and to said basket shaft, and means for operating the clutch whereby when the clutch is engaged the basket shaft is adapted to be driven by the slow speed shaft and the independent motor.

In testimony whereof I affix my signature.
